DESIGN FOR A SLIDE FASTENER TOP STOP

Joseph Brozek, Jackson Heights, N. Y.

Application March 9, 1945, Serial No. 118,384

Term of patent 14 years

(Cl. D17—8)

● *To all whom it may concern:*

Be it known that I, Joseph Brozek, a citizen of the United States, residing at Jackson Heights, Long Island, in the county of Queens, and State of New York, have invented a new, original, and ornamental Design for Slide Fastener Top Stops, of which the following is a specification, reference being had to the accompanying drawing, forming part thereof.

In the drawing—

Fig. 1 is a plan view of a slide fastener top stop, showing my new design in an assembled position on a fragment of a fastener disclosed in broken lines.

Fig. 2 is an enlarged plan view of a top stop as shown in Fig. 1 prior to assembly as shown in Fig. 1;

Fig. 3 is a section taken along line 3—3 of Fig. 4; and

Fig. 4 is a view in front elevation of the top stop shown in Fig. 2.

The essential features of my design reside in the parts shown in full lines.

I claim:

The ornamental design for a slide fastener top stop, as shown and described.

JOSEPH BROZEK.
